[57] CLAIM

The ornamental design for an invalid sling, as shown and described.

DESCRIPTION

FIG. 1 is a top plan view of an invalid sling showing my new design;

FIG. 2 is a bottom plan view thereof;

FIG. 3 is a perspective view showing the invalid sling in use;

FIG. 4 is a front elevational view of the invalid sling;

FIG. 5 is a left elevational view thereof;

FIG. 6 is a right elevational view thereof; and,

FIG. 7 is a rear elevational view thereof.

The broken line showing is for illustrative purposes only and forms no part of the claimed design.

FIG.1.

FIG.2.

FIG. 3.

FIG.4.

FIG.5.

FIG.6.

FIG.7.
